Atty's.

UNITED STATES PATENT OFFICE.

HENRY M. MORGAN, JR., OF NORWOOD, MASSACHUSETTS.

ROOFING.

Application filed February 21, 1924. Serial No. 694,188.

To all whom it may concern:

Be it known that I, HENRY M. MORGAN, Jr., a citizen of the United States, residing at Norwood, in the county of Norfolk and State of Massachusetts, have invented new and useful Improvements in Roofing, of which the following is a specification.

This invention relates to roofing, more particularly of that type comprising overlapping courses of elements of sheet material such as the so called asphalt roofing. This material is somewhat flexible and trouble is often experienced from the free lower ends of the elements being bent up by the wind or curling, so as to permit rain, snow and sleet to drive up under them. At least two layers of this material over the entire surface of the roof have hitherto been necessary, therefore, to insure a weatherproof roof.

According to the present invention the necessity of so great an overlap between the courses is eliminated without impairing the weatherproofing capabilities of the roof, a single layer only of the material being required over a substantial proportion of its area. The total area of roofing material required to weatherproof a roof is thus materially reduced, the cost being reduced proportionally.

As heretofore constructed, where rectangular elements have been employed, they have been in overlapping relation only between superposed horizontal courses. In the construction of the present invention the horizontal adjacent individual elements are also in overlapping relation, and are interlocked both laterally and vertically so that their edges can not raise and permit the weather to reach the interlying roofing foundation.

For a more complete understanding of this invention reference may be had to the accompanying drawings in which—

Figure 1 is a perspective of one of the roofing elements.

Figure 2 is a fragmentary perspective illustrating the manner in which units adjacent to each other horizontally and vertically are interlocked.

Figure 3 is a fragmentary perspective of a portion of a roof laid up with these units.

Each roofing element comprises a rectangular piece of substantially flat sheet roofing material of substantially uniform thickness from side to side as at 1 having its lower corner at one edge cut out as at 2 in rectangular formation. At any desired distance above the upper edge of this cut-out 2 is a mark 3 which may, if desired, be in the form of a slit. Extending forwardly from the opposite side edge of a unit is a slit 4 substantially in alignment with the upper edge of the cut-out 2 defining a laterally directed tab 5. In order to prevent tearing of the material it is preferable to perforate the element at the inner end of the slit as shown at 6, it being noted that the slit 4 merges with the perforation 6 at its upper portion. Substantially midway of the width of the sheet is an angular slit 7 having a portion 8 extending perpendicularly inwardly from the lower edge of the unit and a portion 9 extending from the upper end of the slit portion 8 toward the slit 4. The inner end of the slit 9 also, preferably, terminates in a perforation 10.

The elements are laid on the roof in overlapped interlocking relation in horizontal courses as indicated in Figures 2 and 3, the tab 5 being bent backwardly and passed under the complementary edge of the adjacent element of the same course inwardly of the cut-out 2 while the portion 11 of the side edge above the slit 4 overlaps the edge portion 12 above the cut-out 2 of the adjacent unit. The units are held to the roof by nails, one of which is driven at a between the cut-out 2 and the mark or slot 3 before the next adjacent unit is interlocked therewith, and the other being driven through the upper diagonally opposite corner as at 8. The laterally directed tab 15 formed by the angular cut-out 7 of each element of each course is brought under the edge portion 11 of a unit of the course beneath, each superposed element being moved downwardly until the mark 3 thereon coincides with the upper edge of the element of the underlying course. This mark 3 is merely to give an

indication of the amount of overlap between the successive courses. By causing the slits to terminate eccentrically of the perforations the exposed edges of the units at the slots when laid are straight so that the perforations are not noticeable though they do act to render tearing of the material less likely.

Because of the nails driven at the points 10 *a*, the lower edges of the elements are held down tightly to the roof adjacent their mating side edges, while the tabs 15 fitting beneath the edge portion 11 of the underlying course adjacent to the nails *b*, insures that 15 the central portions of the elements at their lower edges shall also be held down firmly to the roof. Each element is therefore held to the roof at three points along its lower edge, either directly, or by its interlocking 20 connection with an adjacent element close to where this latter element is directly held and without the necessity of folding the material.

By positioning the tabs 15 substantially 25 midway of the side edges of the elements, the overlapping side edges of the element in adjacent courses are staggered as is clearly illustrated in Figure 8.

By effecting this interlocking lapping relation between the individual elements of 30 each course and the elements of adjacent courses, a single thickness of roofing material only is positioned over a substantial proportion of the roof area, the elements being 35 held together in such a manner that more overlap is not necessary to provide a weather-proof roof. It will be noted that none of the nails are exposed to the weather when the roof is laid as they are covered by overlying elements.

Having thus described an embodiment of 40 this invention it should be evident to those skilled in the art that various changes and modifications might be made therein without departing from its spirit or scope as defined by the appended claims.

I claim:

1. A roof comprising roofing elements substantially flat from edge to edge laid in overlapping courses, each element having portions of its edges overlapping and underlapping the adjacent edge of an element of the same course and a portion formed to underlap an element of the next adjacent 55 underlying course.

2. A roof comprising roofing elements laid in overlapping courses, each element having a slit extending inwardly from one side edge defining an upper portion constructed to 60 overlie the adjacent edge of an element of the same course and a lower portion formed to underlie said edge, and having an angle slot extending inwardly from its lower edge to form a laterally directed tab engageable 65 beneath an upper side edge portion of an

element of the underlying course overlying the adjacent edge of its next adjacent element of the same course.

3. A roofing element comprising a rectangular piece of sheet material having a 70 rectangular portion cut from one of its lower corners, a slit cut in from its opposite side edge in substantial alignment with the upper edge of said rectangular cut-out, and an angular slit extending upwardly from its 75 lower edge and then toward said side edge slit.

4. A roof comprising overlapping roofing elements, each of said elements having an 80 angle slit extending inwardly from one edge and defining a tab engageable beneath the edge of another element overlapped by said tab carrying element.

5. A roof comprising overlapping roofing elements, each of said elements having an 85 angle slit extending upwardly and laterally from its lower edge and defining a tab engaging beneath the upwardly extending edge portion of an overlapped element.

6. A roof comprising overlapping roofing 90 elements, each of said elements having an angle slit extending upwardly and laterally from its lower edge and defining a tab engaging beneath an edge portion of an overlapped element.

7. A roof comprising courses of overlapping elements, a plurality of fasteners passed through each element for fixing said element in position, each of said fasteners being covered by an overlapping element and each of said overlapping elements having a portion adjacent to the fastener overlapped by that element underlying the element through which the fastener passes.

8. A roof comprising courses of flexible 100 overlapping elements, a plurality of fasteners passed through each element for fixing said elements in position, each of said fasteners being covered by an overlapping element having means adjacent to said fastener for 105 interlocking with the element through which the fastener passes.

9. A roof comprising overlapping courses of elements, a pair of fastenings passed 110 through each element for retaining said element in position, one of which fastenings is adjacent to the lower edge of said element, and each element overlying a pair of fastenings passing through adjacent elements.

10. A roof comprising overlapping courses of elements, a pair of fastenings passed 115 through each element for retaining said element in position, one of which fastenings is adjacent to the lower edge of said element, and each element overlying a pair of fastenings passing through adjacent elements and interlocked adjacent to said fastenings with said elements.

11. A roof comprising overlapping courses 120 of elements, a pair of fastenings passed through each element for retaining said element in position, one of which fastenings is adjacent to the lower edge of said element, and each element overlying a pair of fastenings passing through adjacent elements and interlocked adjacent to said fastenings with said elements.

through each element for retaining said element in position, one of which fastenings is adjacent to the lower edge of said element, each element overlying near its lower edge a pair of fastenings passing through adjacent elements.

12. A roof comprising overlapping courses of elements, a pair of fastenings passed through each element for retaining said ele-

ment in position, one of which fastenings is 10 adjacent to its lower edge, each element overlying near its lower edge a pair of fastenings passing through adjacent elements, and interlocked adjacent to said fastenings with said elements.

15 In testimony whereof I have affixed my signature.

HENRY M. MORGAN, JR.

through each element for retaining said element in position, one of which fastenings is adjacent to the lower edge of said element, each element overlying near its lower edge a pair of fastenings passing through adjacent elements.

12. A roof comprising overlapping courses of elements, a pair of fastenings passed through each element for retaining said ele-

ment in position, one of which fastenings is 10 adjacent to its lower edge, each element overlying near its lower edge a pair of fastenings passing through adjacent elements, and interlocked adjacent to said fastenings with said elements.

15 In testimony whereof I have affixed my signature.

HENRY M. MORGAN, JR.

Certificate of Correction.

It is hereby certified that in Letters Patent No. 1,567,538, granted December 29, 1925, upon the application of Henry M. Morgan, jr., of Norwood, Massachusetts, for an improvement in "Roofing," an error appears in the printed specification requiring correction as follows: Page 1, line 40, for the word "interlying" read *underlying*; and that the said Letters Patent should be read with this correction therein that the same may conform to the record of the case in the Patent Office.

Signed and sealed this 26th day of January, A. D. 1926.

[SEAL.]

WM. A. KINNAN,
Acting Commissioner of Patents.
